KEY BLANK HOLDING CABINET

Lennie G. W. Morgan, Bonham, Tex.

Application April 10, 1934, Serial No. 719,972

9 Claims. (Cl. 312—183)

This invention relates to devices for holding key blanks in systematic order and particularly to a cabinet for this purpose.

Heretofore key blanks in a locksmith's shop or other place where keys are formed have been kept in compartmented drawers or in bundles on hooks against the wall, thus permitting the key blanks to be readily misplaced and mixed up or a whole drawer full to become "pied" or if hung on hooks permitting the displacement of the blanks or their interchange.

Furthermore, the hooks did not permit a sufficiently large assortment of key blanks to be kept with any economy of space even where the key blanks themselves are supported in bunches on the hooks.

The general object of my invention is to provide a cabinet for this purpose which, while holding a large assortment of blanks for convenient access, is yet particularly compact.

Another object is to provide a cabinet so constructed that any desired blank may be readily found or put back by reference to index numbers associated with the various leaves of the cabinet and in this connection to provide means for retaining in the cabinet an index or catalogue of the blanks so that this will not become lost or misplaced.

A further object is to provide a cabinet of this character having a circular outer casing, a central shaft and a plurality of leaves swingingly mounted upon the central shaft so that they may be crowded against each other while one leaf is being used, the cabinet having a circumferentially extending door permitting access to the interior but capable of being closed and locked to prevent unauthorized meddling with the contents.

A further object in this connection is to provide each main leaf of the cabinet with a pair of hinged leaves, one on each side of the main leaf which, when the main leaf is brought around to the door opening, may be readily opened out so that access may be had to these hinged leaves and the keys supported thereon, the main leaf and the hinged supplementary leaves carrying key blanks which are in some way related to each other.

A still further object is to provide means on the several leaves for supporting pockets in which the keys may be kept, pockets in which memoranda may be kept or particularly clasps or clips upon which the key blanks may be kept, these clasps or clips being so constructed as to permit the ready intentional removal of the keys there-

from but prevent the keys from falling off of the clasp even when the clasp is opened and which is further so constructed that while it may be detached from the leaf upon which it is mounted, this detachment can only occur after a proper manipulation of the clasp. 5

Other objects will appear in the course of the following description.

My invention is illustrated in the accompanying drawings, wherein:—

Figure 1 is a top plan view of the cabinet;

Figure 2 is a horizontal sectional view thereof, the leaves being shown in top plan view;

Figure 3 is a fragmentary section on the line 3—3 of Figure 1;

Figure 4 is a section on the line 4—4 of Figure 2;

Figure 5 is a fragmentary perspective view of one of the main leaves and the supplementary leaves hinged thereto;

Figure 6 is a fragmentary vertical section 20 through the base of the cabinet and through the sleeves surrounding the shaft;

Figure 7 is a vertical sectional view on the line 7—7 of Figure 4;

Figure 8 is a fragmentary perspective view of 25 one of the leaves with the clasp thereon, the clasp being closed;

Figure 9 is a like view to Figure 8 but showing the clasp opened and raised;

Figure 10 is a perspective view of a pocket which 30 may be detachably connected to the leaf by the same means used for holding the clasp;

Figure 11 is a perspective view of a different form of pocket;

Figure 12 is an elevation of a memorandum or 35 bill clamp which is capable of being mounted upon the leaf in place of either the clasp or pocket.

Referring to these drawings, 10 designates a base of wood, metal or any other suitable material and 11 designates the outer casing having a top 40 12. This outer casing at its lower end surrounds a basal element 13 of wood or other suitable material inserted into a recess in the base 10. The lower edge of the sheet metal 11 is held to the element 13 by screws or like means and the bottom 14 is held to this element 13 by screws. As shown in Figures 1 and 2, the outer casing is 45 cylindrical in form but is formed with a door opening 15 which is preferably equal in length to approximately a quarter of the circumference of 50 the casing. Extending through the center of the casing is a shaft 16, the lower end of which is screw-threaded and extends through the elements 10 and 13 and is provided with a nut 17. The upper end of this shaft is also screw-threaded at 55

18, passes through the top 12 of the casing and is provided with a nut 19. Surrounding this shaft and extending through the casing is a sleeve 20 which at its lower end rests upon the bearing balls 21, the shaft having a skirt 22 engaged by a nut 23. The door 24 shown in Figure 4 is arcuate in form to conform to the curvature of the casing and is provided with the upper and lower sector-shaped supporting members 25 and 26, the member 25 being provided with a collar 27 engaging around the upper end of the shaft and the member 26 as shown in Figure 6 engaging around the skirt 22 and being held in place by the nut 23. Thus the door may be swung across the opening 15 or swung to the position shown in Figure 2 to disclose said opening.

The leading edge of the door is provided with an outwardly extending flange 28 and the casing is provided with a like flange 29 so that the door may be locked closed by the passage of a hasp of a lock through these flanges.

The upper and lower ends of the sleeve 20 are provided with outwardly projecting flanges 30, these flanges being perforated at relatively close intervals. Extending through the perforations of the upper flange 30 are the shanks of wire loops 31, the shanks extending downward through the perforations and being headed or otherwise formed to prevent their removal from the perforations. The loops 31 are thus disposed radially around the shaft or sleeve.

Adapted to be engaged with the lower flange 30 and supported by the loops 31 are a plurality of main leaves 32 of sheet metal. Each of these leaves adjacent its upper inside corner is formed with a notch or slot 33 extending downward and inward and with which the loops 31 are adapted to be engaged. The lower inside corner of each leaf 32 is formed to provide a downwardly extending pin or stud 34 (see Figure 6) which is inserted in a perforation in the lower flange 30. It will thus be seen that each leaf 32 is mounted for swinging movement relative to the other leaves and that all of the leaves are mounted for rotational movement with the sleeve 20 around the shaft 16.

Intermediate the several main leaves are spacer leaves 35. Thus these spacer leaves 35 separate each main leaf from an adjacent main leaf. In addition to the spacer leaves and the key supporting leaves 32, I also provide one or more leaves 36 which can take the place of the spacer leaves 35 in separating two adjacent key supporting leaves from each other, these leaves 36 being arranged as will be later described to hold indexes, catalogues or the like.

At the upper and lower ends of each leaf 32, outwardly projecting ears 37 are formed and hingedly engaging these ears 37 are supplementary or hinged leaves 38, there being a hinged leaf 38 on each side of a main leaf 32. The leaves 38 are angular in top plan view as shown in Figures 2 and 5 so that the leaves 32 and 38 will be held in parallel relation to each other when desired, the hinge connection, however, permitting the leaves 38 to be moved out into a right-angular relation to the main leaf 32 when desired.

The main leaf 32 carries upon it at its upper end a tab or shield 39 having thereon a letter, numeral or other index character and the hinged leaves 38 associated with each main leaf 32 carry upon them like shields or tabs 39 but having the letters "L" and "R" thereon respectively for 75 "left" and "right".

For the purpose of supporting keys upon these leaves 32 and 38 and preferably upon both faces of the leaves, I provide eyes 40, the shanks of which extend through the leaves as shown in Figure 7. These eyes are arranged in pairs upon the leaf and it will be seen from Figure 7 that there will be eyes on each side of the leaf. These eyes may be conveniently formed by cotter pins inserted through openings in the leaf or sheet, the legs of the cotter pin being then bent on one side to form an eye opposed to the regular eye of the cotter pin. This is shown in Figure 7.

The eyes are spaced at regular distances apart and adapted to be engaged with these eyes are key supporting slips of wire, one of which is shown in Figure 8 and designated 41. Each key supporting clip has a supporting bar 42 adapted to be passed through the eyes 40, the clip being rectangular in form to provide a lower bar 43 upon which the keys are supported and provide an upwardly extending end portion 44 hooked at its extremity to hook over the bar 42. These clips are made of resilient wire so that when the portion 44 is unhooked from the bar 42, the clip will open, but it will be seen that when the clip is opened as shown in Figure 9, the keys cannot slip off of the clip. This is shown in Figure 4. Each key must be deliberately removed from its clip and even though the clips be left accidentally open, the keys will not drop off and become mixed up.

The extremity of the bar 42 is angularly bent as at 45, this angularly bent portion 45 acting to obstruct or prevent the longitudinal movement of the bar 42 through the eyes 40 unless the clip is deliberately turned upward to the position shown in Figure 9 with the portion 45 against the leaf 32 or 38 as the case may be.

While I have designed the clip 41 as the best and most convenient manner of supporting a number of key blanks, yet, as shown in Figure 10, a pocket 46 may be used for this purpose formed of sheet metal or other material and having key slots 47 in the back thereof spaced a sufficient distance apart so that the eyes 40 may be inserted through the key hole slots and then the eyes 45 turned as to lock the pocket in place.

In Figure 11 I have shown another means which may be used for supporting any flat articles which are indexed to be found in such a numbered receptacle, these receptacles carrying numbers or letters. This pocket which is designated 48 may be formed of metal or any other material, the back is provided with the key hole slots 47 as previously described and the pocket is divided into a plurality of compartments by vertical partitions 49.

In Figure 12, I show a spring clamp which may be readily disposed in place of the clips 41, the pocket 46 or the pocket 48, this clamp consisting of a single piece of wire bent to form the clamping portion 50, the springs 51, the laterally extending shanks 52 which are adapted to extend through the eyes 40 and the upwardly extending portions 53 of the shanks which are adapted to bear against the leaf so that when the clamp portion 50 is pulled outward, the resilience of the springs 51 will act to resist the outward movement of the clamp. These clamps 50 may be conveniently used for holding memoranda, bills or the like which may relate to the particular blanks supported on any particular leaf.

It will be seen from Figure 4 that numerals are placed upon the leaf in association with each particular clip 41, these numerals indicating the consecutive holder locations on that particular

sheet and being referred to from or in the catalogue index as, for instance, "Key blank #1026, AL 10". This would indicate that the article was on the main sheet A, side sheet L and holder 10.

5 These clips may also be used for holding memoranda tags 54 as shown in Fig. 4 or signals indicating that it is time to order new key blanks of this particular variety.

10 The clips may be of different lengths so as to support more key blanks of one kind on one clip than other key blanks less likely to be used. The key blanks will be supported on opposite faces of the leaves 32 or 38 so that one set of three leaves may support a very large number of key blanks, 15 it being intended to file keys without relation to each other but relying solely on the pictured blank in the catalogue being properly indexed and numbered so as to show on which leaf and on which holder the particular blank may be found. 20 That portion of each main leaf 32 rearward of the hinged connection with the lateral leaves 38 may also be used for carrying memoranda or the like by the provision of hooks 55 extending through the main leaf as shown in Fig. 5. The leaves 36 25 are particularly designed for the purpose of supporting catalogues, pricelists or other data relating to key blanks. These leaves 36 have attached to them on each side an angularly bent sheet of metal designated 56 which constitutes a compartment or compartments extending parallel to the sheet 36. The space defined by the wall 56 may be divided into two compartments by a partition 57 shown in dotted lines in Figure 4, if desired. Thus data relating to the key blanks or locks for 30 which the key blanks are to be made, etc., may be kept associated with the key blanks in the cabinet.

35 It will be seen that I have provided a cabinet wherein thousands of keys may be kept in regular order without danger of becoming intermixed. 40 This is for the reason that when any key is desired, it is necessary to open one of the clips and detach the particular blank from the clip and the blank may be readily placed back on these clips, if necessary, the fact that the clips have to 45 be opened preventing carelessness in putting the blank back. Where there are simply compartmented drawers or hooks, the key is liable to be thrown into the compartment without the necessity of this deliberate finding of the correct 50 clip. While the clips can be removed from the respective leaves, yet because of the difficulty of removing the clip, it is not likely that the clip will be removed accidentally or without deliberate forethought for a good reason as the key blank may 55 be readily removed from the clip without removing the clip from the leaf.

With this cabinet, it is an easy matter to add leaves, assuming that the size of the cabinet permits it or remove leaves so as to have no empty 60 or useless leaves within the cabinet or so as to add leaves thereto in case more sizes or keys of different characters must be carried, but this is not ordinarily desirable.

65 It will be seen from Figure 2 that the spacers or partitions 35 prevent the keys on the confronting leaves 38 from becoming entangled with each other and being caught with each other. These separators or spacers 35 play an important 70 part also relative to what may be called the mass rotation as this could not be accomplished should a lateral leaf 38 be disposed to swing in operation. With the separators or spacers 35, the lateral leaves 38 bear against the separators 35 and the hinged lateral leaves swing to a closed position

whereas if no separators 35 were used, the lateral leaves would tend to catch on each other.

Because of the fact that the inner ends of the lateral leaves 38 are angularly bent, the bodies of these leaves are held in spaced relation to the main leaf and this prevents the keys from becoming entangled or mix with each other. As will be seen from Figure 2, either one of the auxiliary hinged leaves 38 may be turned backward so that access may be readily had to the inside face of this leaf or to the confronting face of the main leaf and in fact when the main leaf is in a medial position with reference to the opening 15, both leaves may be turned back sufficiently far to permit ready access to the keys on the inner face of the leaves.

10 By providing the bar 42 on each clip or holder 41 with a bent portion 45 which extends outward at an angle of about 25°, the pin will not pass through the cotter eyes 40 until the free part of 20 the pin or clip is raised out away from its normal position as shown in Figure 9. By lifting the body of the holder outward and upward, the end 45 of the bar 42 may be readily slipped back out of the eyes.

25 This is not done for the purpose of permitting a bunch of keys to be removed but this is only done when interchanging a larger holder or clip of greater capacity for a shorter one. For instance, a year's stock of some particular key 30 blank may consist of only two blanks whereas some of the more popular car keys necessitate the stocking of a gross of key blanks at a time. It is an easy matter, therefore, to rearrange the 35 clips of holders that they may be grouped or re-grouped as to capacity for individual need.

38 The leaves 32 and 38 may have a plurality of holes through them so as to permit rearrangement of the eyes 40 closer to or further apart from each other to permit clips of smaller or 40 larger capacity to be used. The lateral leaves which have a width of about three-fifths that of the main leaves are disposed normally in parallel relation to the corresponding main leaf a distance of approximately twice the diameter of 45 articles desired to be stored or filed. This very greatly increases the storage capacity of the leaves and the fact that these lateral leaves are pivotally mounted on the main leaves allows practically a flat or front view of any leaf.

50 The main leaves are preferably lettered for index reference with the letters A, B, C, D, etc., while the left side leaves carry the letter "L" and the right leaves carry the letter "R". Blank and index pocket sheets are numbered 1, 2, 3, 4, 5 and 55 6, referring to the numbers on the leaves adjacent the key clips. Thus in order to locate immediately a key blank listed as "No. 1500" in the manufacturer's catalogue we give this key blank as index number "BL1". In order to find this 60 blank, we turn the leaves, stop at the main sheet "B", push the side leaf "L" to the right, thereby exposing the No. 1 holder to view on which the "#1,500" blanks will be found and in case the clip from which this blank is taken is left unhooked, 65 the articles will not spill or slide off of the clip owing to the formation of the clip as previously described.

Letters L and R are used to identify at once 70 from corresponding like letters placed along the cuts or pictures of said articles in the manufacturers' catalogue, as for instance, on catalogue of the Independent Lock Co., #10 Key Blank No. 1026 is listed, for instance, on page 83. I index 75 this blank by adding to this catalogue listing

listing letters corresponding to the holder location in the cabinet. Assuming that an empty holder is found on the left side leaf of main sheet "A", I note the number of the holder as painted on the leaf as being #10 and we then add this to the catalogue listing as AL10 denoting that we have that particular blank filed on the left side sheet of main sheet A. Pictures or cuts in catalogues kept by the locksmith, which cuts carry no index extensions indicate that those keys are not in the shop. Those that are indexed are found instantly, thus permitting the locksmith to wait on a customer promptly and at a profit or avoid time consuming searches with no success.

The spacer leaves or separators are also indexed as these leaves may be used for holding any key cutting data which data continually comes to the locksmith as new model locks are devised and applied. Thus each year, new model cars are put out and the locks on these cars require that a locksmith shall have data relating to how to pick these particular locks and how the keys can be duplicated. This information is written out and pasted or otherwise attached to the separator leaves and when so placed, is convenient for examination and is so indexed beside the cuts of the new locks as furnished by the lock company catalogues as to be readily found at a great saving of time. Thus, for instance, a picture of a new lock in a catalogue coming to the locksmith's hands may be indexed as "See '1' Left top sketch", meaning see separator leaf #1 on the left side, the sketch at the top and on this separator leaf there is shown a scale detail of the new lock for a certain make of 1934 cars. Thus it will be seen that this cabinet is not only capable of being used for the support of key blanks and other blanks coacting therewith but is capable of supporting for convenient reference all data relating to new or old locks.

The leaves are made removable because in some cases on big jobs or out of town jobs, it may be necessary to take out the leaf having thereon quite a collection of key blanks to select from. The locksmith can then carry the whole sheet containing blanks of that nature to the town where the job is to be performed and then upon his return the leaf may be set back into place in the cabinet. Under ordinary circumstances, however, the sheets or leaves are not intended to be removed as the removal of sheets in the cabinet hinders proper operation as that allows too much "slap" whereas any addition above the prearranged number of sheets over crowds to where operation would be difficult. Of course, in a large business, the sheets in the cabinet may be kept for "live" stock and sheets with key blanks very seldom used or needed might be removed from the cabinet and placed where these sheets could be very readily found if needed. This provides a plan for keeping old and obsolete stock in such condition, however, that the stock may be quickly found if needed.

The tag previously referred to and shown in Figure 4 and designated by the numeral 54 is provided for stock replenishing and may contain the manufacturer's number, movement, with catalogue and page reference and possible such other reference as will properly identify the article without comparison should the last of a specimen be used from a holder.

While I have illustrated certain details of construction and arrangements of parts, I do not wish to be limited to this as obviously many

changes might be made without departing from the spirit of the invention as defined in the appended claims.

I claim:—

1. A cabinet of the character described, including an outer casing having a door opening and a door, a shaft extending through the casing, a sleeve rotatable on the shaft, a series of rigid main leaves detachably and pivotally carried on the sleeve, angularly formed lateral leaves hinged to the main leaves for movement into or out of parallel relation thereto, and article supporting means carried on the main and lateral leaves.

2. A cabinet of the character described including an outer casing having a door opening and door, a shaft extending through the casing, a sleeve rotatable on the shaft, a series of rigid main leaves pivotally carried on the sleeve, a pair of angular leaves hinged one on each side of each main leaf for movement into or out of parallel relation thereto, and article supporting means carried on both faces of the main and hinged leaves.

3. A cabinet of the character described including a support, a vertical rotatable element mounted on said support and having flanges at its upper and lower ends, a leaf detachably and pivotally engaged with said flanges for rotation with the rotatable element and swinging movement independent thereof, lateral leaves disposed one on each side of the main leaf, the rear ends of the lateral leaves being angularly bent and hingedly engaged with the main leaf whereby the main leaf and the lateral leaves may be held in parallel spaced relation, and means on opposite sides of the three leaves for supporting articles on said leaves.

4. A cabinet of the character described, including an outer casing having a door opening and a door, a shaft extending vertically through the casing, a sleeve rotatable on the shaft, a series of rigid main leaves detachably and pivotally carried on the sleeve, angular leaves disposed one on each side of each main leaf, the rear ends of the angular leaves extending inward and being hinged to the main leaf, and a series of spacer leaves detachably and pivotally connected to the sleeve and disposed between each set of main and lateral leaves, the main and lateral leaves having means whereby articles may be suspended therefrom.

5. In a cabinet of the character described and having an article supporting leaf, eyes projecting from the leaf and a clip upon which articles may be supported, said clip being formed of resilient wire and bent to form a rectangular figure, one bar of the clip being adapted to pass through the eyes, the parallel bar of the clip having a portion extending to the first named bar and a hook to engage thereover, the free end of the first named bar being angularly bent outward whereby it will wedge against the eyes through which the supporting bar is passed and prevent the withdrawal of the clip until the clip is turned with the angular portion thereof against the leaf.

6. A clip upon which articles may be supported formed of resilient wire and bent to form a rectangular figure, one bar of the clip being formed for support, the parallel bar of the clip having a portion extending to the first named bar and a hook to engage thereover, the free end of the first named bar being angularly bent outward.

7. A cabinet of the character described includ-

ing an outer casing having a door opening and a door, a shaft extending vertically through the casing, a series of rigid main leaves in normally radial relation to the shaft, means for supporting the main leaves for rotation as a unit around said shaft, and for individual swinging movement, and lateral leaves hinged on the sides of the main leaves for swinging movement into and out of parallel relation thereto.

10 8. A cabinet of the character described including an outer casing having a door opening and a door, a vertical shaft extending through the casing, a series of rigid leaves in radial relation to the shaft, means at the lower ends of the leaves for operatively supporting said leaves for rotation as a unit around the shaft and for individual swinging movement, and means for supporting the upper ends of the leaves for rotation around the shaft as a unit and for individual swinging movement comprising a member rotatably mounted upon the shaft and having a series of openings and looped links having their inner ends rotatably engaged in said openings, the 25 upper ends of the leaves having downwardly and

inwardly inclined slots with which the loops of the links engage.

9. In a cabinet, a base having a central boss, a casing wall carried on the base and having a door opening, a removable top for the casing wall, a shaft extending vertically through the base and through said top and having a nut holding the top in place, a sleeve surrounding the shaft and at its lower end enlarged and extending downwardly over the boss for rotation thereon, a nut 10 engaging the lower end of the enlargement on the sleeve, the sleeve having a flange above the nut, the upper end of the sleeve having a flange, leaves detachably and pivotally engaging with the first and second named flanges, and a door 15 disposed within the casing wall and having upper and lower sector-shaped portions disposed adjacent the base and top respectively, the lower of said sector-shaped portions embracing the enlarged lower end of the sleeve above the nut 20 thereon and being supported by said nut, the upper sector-shaped portion embracing the shaft below the top for turning movement on the shaft.

LENNIE G. W. MORGAN. 25
